TIME-DELAY ELECTRIC FUSE

Kenneth W. Swain, Hampton Falls, and Elmer H. Taylor, Newburyport, Mass., assignors to The Chase-Shawmut Company, Newburyport, Mass., a corporation of Massachusetts

Application March 1, 1949, Serial No. 78,966

9 Claims. (Cl. 200—123)

1

This invention relates to improvements in fusible protective devices for electrical circuits. More particularly it relates to improvements in electric fuses of the general type wherein substantial time delay is provided on moderate overloads without recourse to mechanical cut-out mechanisms which add materially to production costs. The invention utilizes known thermal characteristics of different fusible materials, combining two such materials in a fusible element in a manner to attain substantially more time delay on moderate overloads as compared with prior comparable fusible elements.

Time delay in electric fuses of the general type to which the invention relates is attained to some extent on moderate overloads as a natural and unavoidable result of the design of their fusible elements which, in the form of strips or fuse links, ordinarily have one or more fusing regions of reduced cross-section with adjacent regions of larger cross-section which necessarily provide some time delay by absorbing heat generated at the reduced regions. The amount of time delay may be increased by increasing the cross-sectional area of the regions adjacent to a reduced cross-section region of fusing and this has been accomplished sometimes in the past by addition of a heat-absorbing mass to the fusible element. However, every commercial fuse is required to have a rating which is determined in accordance with its ability to carry indefinitely a current equal to 110% of its rating, and its ability to interrupt the circuit within one hour when subjected to a current equal to 135% of its rating. Hence, if a particular fuse, having a particular rating, provides an inadequate amount of time delay on moderate overloads, the natural step toward increasing time delay is to increase the cross-section of the fusible element adjacent to its fusing region or regions, or to add heat-absorbing material to the fusible element adjacent to its fusing regions. This accomplishes increase in time delay but, heretofore, it has also changed the rating of the fusible element. It then has been necessary to reduce the cross-sectional area at the fusible region or regions if the modified fusible element is to have the same rating as the original element, and this necessarily reduces the time delay which had been built up. But, a major difficulty in designing a fusible element which will have a predetermined rating and yet provide a desired amount of time delay on moderate overloads derives from the fact that there are limits below which the fusible regions of fusible elements may not practicably be reduced in efforts to attain a particular rating in conjunction with particular time delay characteristics. And, conversely, there are limits above which the heat-absorbing mass characteristics of a fusible element may not be raised when the

2

element is required to have a particular rating. Because of these limits, especially in fusible elements having relatively low ratings, such as thirty amperes and below, for example, the attainment of desirable substantial time delay on moderate overloads heretofore has required introduction of relatively expensive mechanical cut-out mechanism for interrupting a circuit on moderate overloads.

10 It is among the objects of the present invention to provide fusible protective devices wherein a fusible element of one material has a mass of another material associated therewith for providing substantial time delay on moderate overloads, and wherein the fusible element has the same rating before and after association of the said mass therewith. According to the invention, a fuse strip or link of one material, such as zinc or silver or copper, is designed to have a particular rating, and a mass of another fusible material, such as tin or cadmium, or alloys thereof, is attached to the fuse strip or link at a reduced cross-section region thereof to substantially delay fusing of the strip or link on moderate overloads without increasing the rating of the strip or link above its initial particular rating.

Another object is to provide a fusible protective device wherein a fusible element of fusible material having one melting temperature is designed to have a predetermined rating, and wherein a mass of another fusible material of substantially lower melting temperature is attached to the fusible element at a reduced cross-section region thereof, said attached mass having the character that it substantially delays fusing of the element in response to moderate overloads without appreciably increasing the time of fusing of the element in response to overloads up to 135% of the rating of the fusible element without the attached mass thereon. The invention utilizes the known principle of associating fusible alloyable materials of different melting temperatures to effect a fusing of the higher melting temperature element at a temperature substantially below its said melting temperature in response to moderate overloads, but the time-delaying mass has the character whereby its addition to the fusible element leaves the rating of the element the same before and after the addition.

50 Yet another object of the invention is to provide a fusible protective device wherein a fusible strip is designed to have a predetermined rating and has at least one region of reduced cross-section, and wherein a mass of another fusible material, of lower melting temperature than the element, is fixed on the element at a said reduced cross-section region thereby to provide substantially delayed fusing of the element in response to moderate overloads without appreciably affecting the ability of the element to interrupt, within an

hour, a current equal to or greater than 135% of the said predetermined rating of the element.

A still further object is to provide a fusible element for electric fuses wherein a fusible element has at least one region of reduced cross-section, and wherein a mass of another fusible material, which is alloyable with the element material and of lower melting temperature, is mounted on the element at a said region of reduced cross-section, for delaying fusing of the element in response to moderate overloads, and wherein a fluxing agent intervenes between adjacent surfaces of said element and said mass for further delaying fusing of the element in response to moderate overloads.

It is, moreover, our purpose and object generally to improve the structure and fusible characteristics of fusible protective devices and more particularly such devices having substantial time delay on moderate overloads.

In the accompanying drawing:

Fig. 1 is a top plan view of a plug-type fusible protective device embodying features of the invention;

Fig. 2 is a medial cross-sectional view on line 2—2 of Fig. 1;

Fig. 3 is a perspective view of the fusible element of the device of Figs. 1 and 2 prior to addition of the time delay mass thereto;

Fig. 4 is a view similar to Fig. 3 but with the time delay mass mounted on the element;

Fig. 5 is a fragmentary cross-sectional view on line 5—5 of Fig. 4, on a larger scale;

Fig. 6 is a top plan view of the central portion of a fuse link having a time delay mass mounted thereon but having additional material intervening between the adjacent surfaces of the fuse link and mass;

Fig. 7 is a fragmentary cross-sectional view on line 7—7 of Fig. 6; and

Fig. 8 represents two comparative fusing curves of two 20 ampere elements of the varieties of Figs. 3 and 4, with the area of increased time delay in the moderate overload zone cross-hatched for emphasis.

Referring to the drawing, a fusible element 10 is shown in Figs. 1 and 2 as it may be mounted within an insulating casing of a conventional type of plug fuse, with one end of element 10 connected to the center contact 12 and its other end connected, in a well known manner, to screw shell contact 14. It should be understood, however, that the illustrated fuse casing is intended to be merely representative of fuse casings generally, whether of the plug or cartridge types, wherein a fusible element 10 extends between two terminal contacts which are insulated from each other on the casing. As herein shown, two insulating casing sections 16, 18 fit together and are held together by the screw shell contact 14, in conjunction with a soldered connection 20 of the shell contact to one end of fusible element 10. Element 10 extends upward within the casing from the center contact 12, having a substantial central portion laid over upon an insulating disk or plate 22, whence the element extends between the casing sections to its solder connection to the shell contact at 20. Casing section 18 preferably will be of glass so that the laid over portion of element 10 will be visible through the top wall of the section.

According to the invention, the fusible element 10 will be a link or strip of fusible material having a mass 30 of another material mounted thereon at a predetermined location.

In what presently is considered a preferred embodiment, mass 30 is in the form of a rivet made of material having a melting temperature substantially less than the melting temperature of the link material, and having physical properties whereby the link material will become alloyed with the rivet material when the latter melts. But, it is a feature of the invention that the mass 30, in rivet or other form, is added to a link having a particular rating, and that the addition of the mass 30 substantially increases time delay in the moderate overload range without changing the said particular rating of the link.

While it has been proposed heretofore to employ a low melting temperature material, such as cadmium, on a fuse link made of material having a substantially higher melting temperature, such as copper, with the cadmium adhering to the copper and adapted to form an alloy with the copper upon melting of the cadmium, so as to enable fusing of the link in the cadmium-copper alloy region at a temperature substantially below the melting temperature of copper, all of the prior proposals of this general nature, so far as we are aware, have been directed toward reducing the temperature of fusing of relatively high melting temperature fuse links.

The invention utilizes this known alloying principle to effect ultimate circuit interruption on moderate overloads at a temperature substantially below the melting temperature of the link material but, the primary function of the mass 30 in the present invention is to provide substantial time delay in the moderate overload response of a fuse link whose rating is the same both with and without the mass 30, the alloying characteristic being a contributing factor in the attainment of ultimate circuit interruption. The invention makes it practically feasible, for the first time, to provide substantial time delay in relatively low cost fuses by merely adding the time delay characteristics to an ordinary fuse link of the desired ultimate rating without changing that rating.

One commercially practical embodiment of the invention employs a flexible strip of zinc for the fusible element or link 10 as shown in Fig. 3. This strip or link 10 of Fig. 3 may be a 20 ampere fuse link, for example, which is suitable for embodiment in a conventional commercial fuse which provides no substantial time delay on moderate overloads. It has a hole 26 therein located at or near the mid-point between the ends of the link, and has two larger holes 28 equally spaced at opposite sides of hole 26. When this link of Fig. 3, assumed to have a 20 ampere rating, is employed in a conventional manner to provide circuit protection without any substantial amount of time delay on moderate overloads, fusing on moderate overloads ordinarily occurs at the central hole 26 whereas fusing on short circuit provides quick interruption at one or both of the holes 28.

Assuming now that it is desired to provide a 20 ampere link which will provide substantial time delay on moderate overloads, this readily may be accomplished, in accordance with the invention, by taking a Fig. 3 20 ampere link and applying to it, at the region of its central hole 26, a mass of fusible material 30, as illustrated in Figs. 4 and 5. Mass 30 preferably will be tin or a high-tin-content alloy. Cadmium and high-cadmium-content alloys may be used but

we have found that our novel results and effects are definitely more pronounced when mass 30 is tin or has large tin content.

The mass 30 may be associated with the link 10 in various ways but the illustrated rivet-form of mass 30 has the practical advantage that it quickly and effectively may be secured in place in the central hole 26 of a link 10, with its shank filling the hole 26. Such a 20 ampere zinc link 10, with a rivet or comparable mass 30 of tin thereon, as in Figs. 4 and 5, retains its character as a 20 ampere fuse link but acquires substantial time delay in the important moderate overload range, yet it provides the same quick action on short circuit that it provides without the mass 30 thereon. Actually, the link with mass 30 thereon fuses on moderate overloads outward of the mass, usually at one of the holes 28. The mass 30 acts, to some extent at least, as a heat-absorber but, when the mass material and the link material are intimately in contact with each other, as in Figs. 4 and 5, the size of the mass 30 apparently is not too critical because numerous tests have revealed that the mass 30 may be varied considerably in size without appreciably affecting either the amount of time delay or the rating of the element. The action on moderate overloads appears to be that the mass 30 acts as a heat-absorbing mass until it reaches its melting temperature, after which the tin and zinc form an alloy at some region of the link where fusing ultimately occurs at a temperature below the melting temperature of the zinc of the link.

When the tin mass 30 and the link material are intimately in contact with each other, as in Figs. 4 and 5, the amount of time delay attained frequently varies considerably in the individuals of any lot of fusible elements. We have found that greater uniformity is attained, and substantially increased time delay, by introducing an agent in the nature of a fluxing agent between the adjacent surfaces of mass 30 and the link. Such an agent is represented at 32 in Figs. 6 and 7. Rosin is a recommended agent for this purpose, and the rosin may be applied to the mass 30 in powder form by dusting it over the mass surfaces, or rosin dissolved in alcohol may be applied as a liquid to the surfaces of mass 30. Another agent, known commercially as alpha acid, has been dusted over the mass surfaces in dry powder form with good results, but rosin presently is considered preferable.

Introduction of rosin or a comparable agent 32 between the adjacent surfaces of mass 30 and link 10, as in Figs. 6 and 7, considerably modifies the fusing action on moderate overloads as compared with the action of the Figs. 4 and 5 element having no agent 32. Substantially increased time delay is attained as compared with the Figs. 4 and 5 element, and fusing on moderate overloads occurs in practically every instance, at one of the holes 28, with definitely improved results as regards uniformity of time delay. But the element 10 of predetermined rating has the same rating both before and after addition of mass 30 and agent 32 thereto and its short circuit response is the same both before and after addition of mass 30 and agent 32. However, the introduced agent 32 apparently considerably modifies the heat-absorbing effect of mass 30, because variation of the size of mass 30 in an element having agent 32 introduced varies the amount of time delay whereas no appreciable variation in time delay has been observable as accompanying change of size of mass 30 in the Figs. 4 and 5 embodiment.

It is not fully understood why the mass 30, agent 32 and link material react as they do in response to moderate overloads, but it is notable that addition of mass 30 and agent 32 to a rated fuse link 10 like that of Fig. 3 does not increase the rating of link 10 even though the size of mass 30 may vary considerably. It also is a notable fact, demonstrated by numerous tests, that if mass 30 becomes melted and the overload drops off or the circuit is opened before fusing of element 10 occurs, the element, with mass 30 re-solidified, continues to have its original rating and generally the same time delay characteristics. While some alloying of the tin and zinc may have occurred, apparently this has no material effect in subsequent service of the element. The element continues to function, with substantially unchanged time delay characteristics, until such an alloying occurs at one of the holes 28.

In any event, the invention provides inexpensive fusible protective devices having substantial time delay on moderate overloads whose ratings are predetermined apart from the means which provide the substantial time delay, and which will have the same rating before and after addition of the time delay means.

The substantial amount of time delay provided by the invention and its provision in the important moderate overload region where time delay is wanted, will be apparent from an examination of Fig. 8 wherein comparative fusing curves are shown, the curve 34 representing the fusing times, at the indicated currents, of a 20 ampere zinc fuse link like that of Fig. 3, which may be a stock link designed for conventional use without substantial time delay on moderate overloads. Curve 36 represents the fusing times, at the indicated currents, of a 20 ampere zinc fuse link like that of Fig. 3 but equipped, according to the invention, with a tin rivet or mass 30 which preliminarily had been dusted with an agent 32 (rosin) as in the Figs. 6 and 7 embodiment of the invention. The cross-hatched region at 38 shows the important moderate overload region and the very substantial amount of increase in time delay effected by the invention in this important region.

While zinc has been mentioned as a desirable link material, silver or copper links equipped with rosin-dusted rivets 30 provide time delay on moderate overloads comparable to what has been described in connection with zinc fuse links, but the ratings of such silver or copper links, before and after addition of the rivets, will not be the same because of the substantially higher melting temperatures of silver and copper as compared with zinc. But the rosin-dusted tin rivets make it practicably feasible to employ either silver or copper fuse links and to provide time delay characteristics comparable to those of the described zinc links, in the mentioned lower ampere range.

It is presently believed that the agent 32 must have the character of acting as a fluxing agent between the mass 30 and the link material, such as rosin, alpha acid and comparable agents.

It is intended that the patent shall cover, by suitable expression in the appended claims, whatever features of patentable novelty exist in the invention disclosed.

We claim as our invention:

1. In an electric fuse, a fuse link made of fusible material and having a hole therethrough at a central location along the link and two other regions of reduced cross-section equally spaced at opposite sides of said hole, a mass of a lower melting temperature fusible material ap-

plied to the link at said hole and filling the hole, said mass being adapted to substantially delay fusing of the link in response to predetermined overloads, and being of material having the character that, when melted, it will form an alloy with the adjacent link material, and a fluxing agent associated with said mass for delaying the formation of said alloy, said link having the same rating before and after applying of said mass and fluxing agent thereto.

2. In an electric fuse, a fuse link made of fusible material and having at least two high overload fusing regions of reduced cross-section equally spaced at opposite sides of a central location between the ends of the link at which in central location the link is adapted to fuse in response to a moderate overload of predetermined character, there being a hole through the link at said central location, a heat-absorbing rivet secured in said hole at said central location and adapted, upon melting in response to a said moderate overload, to form an alloy with the link material adjacent to a said high overload fusing region whereby the link fuses at a said high overload fusing region, with substantial time delay, in response to a said moderate overload of predetermined character, said rivet having a melting temperature lower than that of the link material and said moderate overload fusing occurring at a temperature below the melting temperature of the link material, and a fluxing agent associated with said rivet for delaying the formation of said alloy, said link having the same rating before and after addition of said rivet and fluxing agent thereto.

3. In an electric fuse, a fuse link made of fusible material and having at least two high overload fusing regions of reduced cross-section equally spaced at opposite sides of a central location between the ends of the link at which central location the link is adapted to fuse in response to a moderate overload of predetermined character, there being a hole through the link at said central location, a heat-absorbing rivet secured in said hole at said central location, a fluxing agent intervening between adjacent surfaces of said rivet and link, said rivet being adapted, upon melting in response to a said moderate overload, to form an alloy with the link material adjacent to a said high overload fusing region whereby the link fuses at a said high overload fusing region, with substantial time delay, in response to a said moderate overload of predetermined character, said rivet having a melting temperature below that of the link material, and said fluxing agent delaying a said moderate overload fusing at a said alloy region of the link, the moderate overload fusing ultimately occurring at a temperature below the melting temperature of the link material.

4. A time delay fusible element, comprising a fuse link made of a strip of fusible material having two high overload fusing regions and an intervening moderate overload fusing region, there being a hole through the link at said moderate overload fusing region, a rivet of a lower melting temperature fusible material secured in said hole and adapted to shift the moderate overload fusing region to one of said high overload fusing regions, said rivet being adapted to substantially delay moderate overload fusing and to form an alloy with the adjacent link material, and a fluxing agent intervening between adjacent link and rivet surfaces for further delaying moderate overload fusing, the ultimate fusing of the fuse

link, in response to a moderate overload, occurring at a said alloy region of the link at a temperature substantially below the melting temperature of the link material.

5. A time delay fusible element, comprising a fuse link made of fusible strip material and designed to have a particular rating, a rivet of lower melting temperature fusible material secured to the link and adapted to absorb substantial amounts of heat generated in the link in response to moderate overloads, thereby to provide substantial time delay on moderate overloads, said rivet material having the character that it forms an alloy with the adjacent link material when the rivet melts, and a fluxing agent intervening between the adjacent link and rivet surfaces for further delaying fusing of the link in response to moderate overloads, said link having the same rating before and after addition of the rivet thereto.

6. An electric fuse, comprising a fuse casing having terminals thereon, a fusible element extending within the casing and connected to said terminals, said fusible element comprising a fuse link made of zinc, a rivet of tin secured on the link, and a rosin fluxing agent intervening between the adjacent rivet and link surfaces.

7. A fusible element for electrical protective devices, comprising a fuse link of zinc, a tin rivet secured at a mid-location along the link, and a rosin fluxing agent intervening between the adjacent rivet and link surfaces.

8. A fusible element for electrical protective devices, comprising a fuse link, a mass of fusible material having a lower melting temperature than the fuse link material mounted on said link, said mass of lower melting temperature material being adapted, when melted, to form an alloy with the adjacent material of the fuse link thereby to provide an alloy region in the link at which fusing of the link occurs at a temperature below the melting temperature of the link material, and a fluxing agent intervening between adjacent surfaces of said link and said mass for delaying the said alloying of the link and mass materials.

9. A fusible element for electrical protective devices, comprising a strip of fusible material having a region of reduced cross-section therein, a mass of lower melting temperature material mounted on the strip at said region of reduced cross-section, said mass being adapted, when melted, to form an alloy with the adjacent strip material thereby to provide an alloy region in the strip at which the strip will fuse at a temperature below the melting temperature of the strip material, and a fluxing agent intervening between the adjacent strip and mass surfaces.
